C. P. ROSS.
LIQUID MEASURING DEVICE.
APPLICATION FILED DEC. 31, 1912.

Patented Oct. 28, 1913.

UNITED STATES PATENT OFFICE.

CHARLES P. ROSS, OF SEATTLE, WASHINGTON.

LIQUID-MEASURING DEVICE.

1,077,000.

Specification of Letters Patent.

Patented Oct. 28, 1913.

Application filed December 31, 1912. Serial No. 739,545.

To all whom it may concern:

Be it known that I, CHARLES P. Ross, a citizen of the United States, residing at Seattle, in the county of King and State of Washington, have invented certain new and useful Improvements in Liquid-Measuring Devices, of which the following is a specification.

This invention relates to liquid measuring pump apparatus, and is in the nature of an improvement on the invention forming the subject matter of my prior application filed in the U. S. Patent Office July 13, 1912, Serial No. 709,256.

The object of my improvements is the provision of a device of this character which will be of relatively inexpensive construction and efficient in operation.

The invention consists in the novel construction, adaptation and combination of parts, as will be hereinafter described and claimed.

In the accompanying drawings, Figure 1 is a vertical section of a liquid measurer embodying my invention. Fig. 2 is a similar view of a portion of the lower end of the pump cylinder with the plunger-stop shown in a different position from that in which it is illustrated in Fig. 1; and Fig. 3 is a perspective view of the plunger-stop.

Referring to the drawings, the numeral 5 designates a portion of a barrel or other suitable liquid container. 6 is a draw-off tube provided at one end with screw threads 35 for engagement in an outlet formed in the end of said container. At the outer end of said tube is a spout 7 and intermediate its length is an upwardly directed branch 8 making connection with a superposed cylinder 9.

Partitions 10 and 11 are provided, as shown, within the tube between the branch 8 and the ends of the tube. Said partitions are formed with passages and provided 45 therefor are spring closed inlet and outlet valves 12 and 13 which open outwardly with respect to the liquid container. Operable within said cylinder is a packed piston 14 having a stem 15 which extends through an aperture provided in the cylinder-head 16 and terminates in a handle 17 whereby the piston is operated. The piston stem is characterized by being provided near its upper and lower ends, respectively, with annular

recesses 18 and 19 and therebetween the 55 stem is formed with a series of relatively small alternating annular grooves 20 and ridges or teeth 21.

22 represents a pawl which is inclosed by a casing 23 secured to or formed upon the 60 cylinder head 16. Said pawl is fulcrumed intermediate its length to a pivotal pin 24 which is supported by the casing. A helical spring 25 is connected to an end of the pawl as shown in Fig. 1, and tends to maintain 65 the same in a horizontal position.

When the stem is pulled upwardly to raise the piston, the pawl encounters the teeth 21 and is tilted thereby into the position in which it is indicated by broken lines A until 70 the stem enters the recess 19 at the termination of the upward stroke of the piston; whereupon the pawl is caused by the spring to assume a horizontal position and upon the downward stroke of the piston the teeth 75 21 will affect the pawl to swing it into dotted line position B and thus by engaging the successive teeth in each stroke any reverse movement of the piston is prevented until the pawl enters one or the other of the 80 recesses.

Supplementary to the above explained appliances for preventing reverse movements of the piston before completing the strokes thereof, I provide a device to positively 85 prevent the operation of the piston when the liquid is absent from within the cylinder. To such end, I provide a stop, shown detached in Fig. 3, consisting of a hub 26 through which extends a pivotal pin 27 90 whereby it is supported in a recess provided at the lower end of the cylinder. Extending radially from the hub 26 and into cylinder opening 28 is a disk shaped blade 29 of a diameter slightly less than said opening. At the opposite side of the pin is a relatively heavy arm 30, and extending respectively above and below the pin is a post 31 and a finger 32. When liquid is being ejected from the cylinder through the office 95 of the piston on its down stroke, the liquid will cause the blade 29 to be drawn therewith into the opening until arrested by the finger 32 contacting with the wall of the opening, whereupon the post 31 will be 100 swung toward the axis of the cylinder and in position to enter the cavity 33 provided within the lower end of the piston stem, as 105

clearly shown in Fig. 1. When the liquid, however, is replaced by air within the cylinder, the discharge of the air will escape without overcoming the power of the arm 5 30 which will hold the post 31 in the position in which it is represented in Fig. 2, to be encountered by the piston and prevent the latter completing the downward stroke and while the stem teeth are still engaged by 10 the pawl. The piston cannot then be moved upwardly by reason of the pawl engaging a tooth, nor can it be moved in the opposite direction because of the obstruction due to the post and, consequently, the piston becomes 15 inoperative. To render the apparatus again operative, it must be tilted rearwardly to correspondingly swing the post from engagement with the piston.

The cylinder 9 is constructed to contain 20 a certain quantity, as a half-pint for example, of liquid. Each time the stem 15 is pulled up to its extreme height that quantity of the liquid is drawn into the cylinder by the suction created by the piston and 25 when the piston is pushed down the liquid previously drawn into the cylinder is ejected. The valves 12 and 13 being of the non-return type, accommodate themselves to such flow of liquid to and from the cylinder. It is to be noted, however, that the 30 piston is inoperative to expel any liquid from the cylinder until the latter is completely filled, but the liquid may be discharged in smaller quantities than the capacity of the cylinder until emptied.

What I claim is—

1. In apparatus of the class described, a measuring cylinder provided at one end with an inlet and discharge opening, a piston 40 ton therefor, a stem terminating in a handle for operating the piston, and means engageable with the stem for preventing any reverse movement of the piston before the termination of the successive strokes.
- 45 2. In apparatus of the class described, a pump cylinder having an opening at one end for both the admission and discharge of liquid, a valveless piston for the cylinder, means for reciprocating the piston, said 50 means comprising a stem extending through the cylinder head and formed with a plurality of teeth interposed between two recesses, and a pawl engageable with said teeth whereby the piston is prevented from being moved in a reverse direction before

the recesses of the stem are presented to the pawl at the termination of the successive strokes of the piston.

3. In apparatus of the class described, a measuring cylinder, a piston therefor, a stem 60 for operating the piston, means engageable with the stem for preventing any reverse movement of the piston before the termination of the successive strokes, and means co-operating with the aforesaid means for locking the piston against movement when the supply of liquid to the apparatus is interrupted.

4. In apparatus of the class described, a pump cylinder, a draw-off tube connected with 70 the cylinder, non-return valves provided in said tube for regulating the flow of liquid to and from the cylinder, a piston for the cylinder, a spring-actuated pawl, and an operating stem for the piston, said stem being formed 75 to be engaged by the pawl to prevent reverse movement being imparted to the piston before the termination of the successive strokes.

5. In apparatus of the class described, a 80 pump cylinder, a draw-off tube connected intermediate its length to said cylinder, spring-controlled non-return valves in said tube at opposite sides of its connection with the cylinder, a piston for the cylinder, an 85 operating stem for the piston, said stem being provided in proximity to each of its extremities with a peripheral recess and intermediate the recesses is provided with a 90 series of annular ridges, and a spring-controlled pawl engageable with the said ridges to prevent any reverse movement of the piston before the respective recesses are presented to the pawl at the termination of the successive strokes of the piston.

6. In apparatus of the class described, a 95 pump cylinder, a draw-off tube connected with the cylinder, non-return valves provided in said tube for regulating the flow of liquid to and from the cylinder, a stem for actuating the piston, and means provided within the cylinder for securing the piston against retrograde movement before the termination of its successive strokes.

Signed at Seattle, Wash., this 19th day of December, 1912.

CHARLES P. ROSS.
